UNITED STATES PATENT OFFICE

JULIUS A. MAHR, OF MINNEAPOLIS, MINNESOTA, ASSIGNOR TO INVENTORS' PATENT HOLDING COMPANY, OF MINNEAPOLIS, MINNESOTA, A CORPORATION OF SOUTH DAKOTA

HOOD FOR BABY CARRIAGES

Original application filed December 12, 1928, Serial No. 325,411. Divided and this application filed November 6, 1929. Serial No. 405,115.

My present invention has for its object to provide a simple and highly efficient folding hood for baby carriages and while intended for general use, is especially well adapted for use in connection with my folding baby carriage disclosed and broadly claimed in a co-pending application, filed December 12, 1928, under Serial No. 325,411 of which the present application is a division.

10 To the above end, generally stated, the invention consists of the novel devices and combinations of devices hereinafter described and defined in the claims.

15 In the accompanying drawings, which illustrate the invention, like characters indicate like parts throughout the several views.

Referring to the drawings:

Fig. 1 is a right side elevation of the improved hood mounted on the body of a folding baby carriage;

20 Fig. 2 is a front elevation of the same with a portion of the baby carriage sectioned on the line 2—2 of Fig. 1;

25 Fig. 3 is a fragmentary view of the hood in longitudinal vertical section, on an enlarged scale;

Fig. 4 is a fragmentary detail view of the intermediate section of the hood removed from the central bow;

30 Fig. 5 is a fragmentary detail view with some parts sectioned on the line 5—5 of Fig. 1, on an enlarged scale; and

Fig. 6 is a perspective view of one of the bow supports and attached bows.

35 The improved hood 7 is made from flexible material mounted, as shown, on three metallic tubular bows 8 and attached thereto by flexible cores 9 of any suitable material, for instance manila rope. The hood 7 is attached to the cores 9 by being folded therearound

40 and secured thereto by stitches or other fastening means 10. These cores 9 are mounted in the bows 8 by threading the same endwise therein and longitudinal slots 11 are formed in the inner sides of said bows through which the hood 7 extends, see Fig. 3.

45 The end portions of the bows 8 are flattened at 12 and attached to bow supports in the form of bearing plates 13 pivotally mounted on draw bolts 14 carried by brackets 15 rigid-

ly secured to the sides of the upper frame member 16 of a folding baby carriage body 17, at the longitudinal centers thereof. By reference to Fig. 6, it will be noted that the intermediate bow 8 is rigidly secured to the bearing plates 13 by a pair of bolts 18 and that the outer bows 8 are pivoted thereto by single bolts 19 whereby said outer bows may be folded onto said intermediate bow. The brackets 15, as shown, in Fig. 5, are U-shape 55 in cross section and the inner side members thereof are rolled more than half-way around the frame member 16 and rigidly secured thereto by rivets.

50 The bearing plates 13 extend between the side members of the brackets 15 in contact with the inner faces of the outer side members of said brackets and the bolts 14 extend through bores in said outer side members and are intermediately supported therefrom. To 60 permit the application of the bolts 14 to the outer side members of the brackets 15, large passageways 20 are formed in the inner side members of said brackets. Spring washers 21 are applied to the bolts 14 and bear against the inner faces of the bearing plates 13. Also applied to the bolts 14 between their heads and the washers 21 are short spacing sleeves 22.

65 The outer side members of brackets 15 are outwardly bulged to substantially the same shape as the washers 21 but in reverse order, as indicated at 23, so as to insure good frictional contact between said side plates and the bearing plates 13. Hand nuts 24 are applied to the bolts 14 and by tightening the same, the bearing plates 13 will be frictionally held between the outer side members of the brackets 15 and washers 21 to hold the hood 7 where set.

70 The lower portions of the hood 7 are anchored to the bolts 14 by providing said hood with grommets 25 and mounting the same on the spacing sleeves 22. These spacing sleeves 22 are of such length as to prevent the grommets 25 from being clamped between the heads of the bolts 14 and the washers 21 which would prevent the same from turning during different adjustments of the hood 7 about the axis of the bolts 14.

To hold the outer bows 8 spread in respect to the intermediate bow 8 and thereby hold the hood 7 stretched taut between said bows there is provided at each side of the hood 7 a toggle lever 26. The ends of the toggle levers 26 are pivoted to the outer bows 8 and a U-shape member 27 is attached to each intermediate pivot of the toggle levers 26. Said U-shape members 27 are so arranged that the members of the toggle levers 26 engage the transverse portions of said members during the straightening movements of said levers after their intermediate pivots have passed beyond dead centers to lock the toggle levers 26 with the hood 7 open, (see Fig. 1).

The customary buckle-equipped cross-strap 28 is provided to prevent a baby from falling out of the baby carriage and which strap is releasably secured to apertured lips 29 formed with the inner rolled portions of the brackets 15.

By flattening the ends of the tubular bows 8 a two-ply stock is produced which greatly strengthens said bows where the bolts 18-19 extend therethrough. When flattening the ends of the bows 8, the stock is rolled or turned into the tubular ends of said bows, and against the internal surfaces thereof so as not to obstruct the openings therein. To apply the hood 7 to the bows 8, the cores 9 are first attached thereto and thereafter said cores are inserted endwise into the bows 8 and the hood 7 edgewise into the slots 11.

The toggle levers 36 are attached to the bows 8 before the hood 7 is applied thereto by spreading the bows 8 at their slots 11 where the holes are formed therein for the rivets which pivotally connect the arms of said toggle levers to the bows 8. In applying the rivets to the bows 8 and toggle levers 36, said rivets are inserted through the holes provided therefore in said bows from the inside thereof so that the pre-formed heads on rivets are within the bows thus eliminating all danger of the rivets pulling out as a result of poorly formed heads. The rivets, after the toggle levers 36 are applied thereto, are upset to form heads on their outer ends and which heads are exposed to view so that the same may be readily inspected for defects.

What I claim is:

1. A hood of the class described having a plurality of bows, a pair of pivot plates to which the bows are attached, a pair of U-shaped brackets having on one of their side members means for attaching the same to a supporting body, clamping bolts pivotally connecting the pivot plates to the other side members of the bracket, and washers on the bolts, said bolts being operable to frictionally clamp the pivot plates between the washer and side members of the brackets in which the bolts are mounted, spacers between the heads of the bolts and the washers, and grommets in the hood through which the spacers

loosely extend with freedom to permit said grommets to turn thereon.

2. A hood of the class described having a plurality of bows, a pair of pivot plates to which the bows are attached, a pair of laterally spaced U-shaped members, the inner side members of which are relatively wide and shaped to form seats that are more than semi-circles in cross-section, and applicable to a body member that is round in cross-section, and clamping bolts pivotally connecting the pivot plates to the outer members of the brackets, said seats having apertured lips for attaching a cross strap to the brackets.

In testimony whereof I affix my signature.

JULIUS A. MAHR.
